2 SHEETS—SHEET 2.

UNITED STATES PATENT OFFICE.

JOHN S. BEAVER, OF ENTRIKEN, PENNSYLVANIA, ASSIGNOR OF ONE-FOURTH TO JOHN NEVIN BEAVER, JR., OF ENTRIKEN, PENNSYLVANIA.

WATER-WHEEL.

985,104.

Specification of Letters Patent. Patented Feb. 21, 1911.

Application filed May 2, 1910. Serial No. 558,800.

To all whom it may concern:

Be it known that I, JOHN S. BEAVER, a citizen of the United States, residing at Entriiken, in the county of Huntingdon, 5 State of Pennsylvania, have invented certain new and useful Improvements in Water-Wheels; and I do hereby declare the following to be a full, clear, and exact description of the invention, such as will 10 enable others skilled in the art to which it appertains to make and use the same.

The invention relates to motors and more particularly to the class of water power wheels.

15 The primary object of the invention is the provision of an apparatus of this character in which the power wheel is formed with a plurality of buckets adapted to receive water from a chute, the same being 20 provided with a discharge opening disposed forwardly of the axis of rotation of the water wheel and which opening is adapted to deliver a sheet of water only to a single bucket successively one after the other for 25 effecting the rotation of the water wheel whereby the rotary movement may be utilized as motive power for driving machinery or the like.

A further object of the invention is the 30 provision of a water wheel of the character described in which a stream of water is conveyed from above the wheel into a series of buckets disposed peripherally of the wheel, the buckets being so shaped as to 35 permit the egress of air on the entrance of water therein thus enabling each bucket to receive a supply of water to its fullest capacity whereby a constant and uniform rotation will be imparted to the wheel by the 40 power of force of the water and its weight so that the rotary movement of the wheel may be utilized as motive power.

A further object of the invention is the 45 provision of an apparatus of this character in which the general construction and arrangement of parts are materially improved over apparatus of this class and that may be manufactured at a minimum expense.

With these and other objects in view the 50 invention consists in the construction, combination and arrangement of parts as will be hereinafter more fully described, illustrated in the accompanying drawings, disclosing the preferred form of embodiment

of the invention and pointed out in the 55 claims hereunto appended.

In the drawings:—Figure 1 is a side elevation of a flume and water wheel constructed in accordance with the invention. Fig. 2 is a top plan view thereof. Fig. 3 60 is a fragmentary vertical longitudinal sectional view through the flume and water wheel. Fig. 4 is a transverse sectional view thereof.

Similar reference characters indicate corresponding parts throughout the several views in the drawings.

Referring to the drawings by numerals 5 designates a forwardly inclined flume or chute having vertical side walls 6, a bottom 70 7 extended a considerable distance beyond the forward closed end 8 which is of the same depth as the side walls 6 and slightly inclined rearwardly of the flume. At a distance removed from the closed end of the 75 flume 5 is a cross bar 9 and to this bar and the upper edge of the end 8 are connected a plurality of spaced slats 10 to permit an overflow of water when rushing through the flume. 80

Disposed below the flume at its forward end is a rotary water wheel comprising a hub 11 fixed to a shaft 12, the hub having fixed to its opposite ends outwardly extending radial spokes 13 the same being secured 85 at their outer ends to annular sides 14 disposed at opposite side edges of a cylinder 15 which latter is joined to the sides 14 by means of flange rings 16 secured to the inner faces of the said cylinder and sides. Centrally secured to the inner face of the cylinder 15 is a ring member 17 the same being formed with a central flange 18 to which are secured a plurality of diagonally disposed brace bars 19 the latter being also secured to the spokes 13. The cylinder 15 is formed from a single piece of material bent to provide a series of pockets 20 between the sides 14, each pocket formed with an outwardly bowed or curved front wall 21 so as 100 to extend a considerable distance over the pockets 20 and through the outer ends of these walls 21 are passed transverse bolts 22 which latter also engage the sides 14 to prevent operation thereof. 105

The outer free edges of the sides 14 are bent to form inwardly directed angularly disposed flanges 23 throughout the entire

- periphery of the water wheel, the shaft 12 supporting the wheel is journaled in any suitable bearings and on the rotation of the water wheel the motion thereof is transmitted from the shaft 12 to which the wheel is fixed to machinery or other mechanisms and in this manner the water power may be utilized for power in driving machinery or the like.
- 10 In the bottom 7 of the flume 5 at a point beyond the axis of rotation of the water wheel is a discharge port 24 the latter being of any desirable size so that a sheet stream of water may be delivered to only one bucket 15 at a time when the water in the flume is being discharged through the said port. Secured to the under face of the bottom 7 to one side of the port 24 is a forwardly inclined depending lip or chute 25 the same being disposed in juxtaposition to the side wall of the port 24 so as to direct the water in a forward direction toward the water wheel beyond its axis of movement. At the opposite sides of the port 24 and fixed to 20 the bottom 7 of the flume 5 is a baffled lip or plate 26 so as to interrupt the splashing of the water when issuing through the port 24 and at the same time assure the course of the water toward the water wheel.
- 25 The port 24 in the bottom of the flume 5 is normally closed by a slide valve comprising a plate 27 provided on its upper face with spaced parallel toothed racks 28 meshing with gear wheels 29 fixed to a horizontal shaft 30 journaled horizontally in the flume 5 and having its bearings in the side walls 6 thereof. To one end of this shaft 30 is fixed a beveled pinion 31 meshing with a further pivoted pinion 32 secured to a vertical turning shaft 33 suitably supported from a wall adjacent the flume, the shaft 33 being provided with a turning wheel 34 having the usual crank 35 for manual manipulation.
- 30 It will be noted that the inbent flanges 23

of the sides 14 of the water wheel will prevent the water from escaping or overflowing from opposite sides of the said wheel during the rotation thereof. 45

It is thought that the construction and operation of the invention will be clear and 50 therefore a more extended explanation has been omitted.

In the sides 14 are provided ports 36 communicating with each pocket 20 and these ports are normally closed by slides 37 each containing slots 38 in which are engaged the guide pins 39 mounting the slides on the outer faces of the sides 14 of the water wheel, whereby they may be shifted to open or close the ports 36. The slides are provided with 55 openings correspondingly shaped to the ports 36 so that when the said slides are moved these openings 40 will register with the ports 36 thus permitting the pockets to be drained or to permit the escape of air 60 therefrom when water enters the pocket. 65

What is claimed is:—

1. In a power mechanism, a water wheel having sides spaced from each other and a cylinder disposed between the sides and 70 formed with inbent portions constituting buckets.

2. A water wheel comprising spaced sides, and a cylinder disposed between the sides and secured thereto and formed with inbent 75 portions constituting buckets, and means for holding the buckets spaced from each other.

3. A water wheel comprising spaced sides, a cylinder disposed between the sides and formed with inbent portions constituting 80 buckets, each one of said buckets having a terminal secured to the sides.

In testimony whereof, I affix my signature, in presence of two witnesses.

JOHN S. BEAVER.
